(57) **CLAIM**

The ornamental design for a fuel transfer pump, as shown and described.

DESCRIPTION

FIG. 1 is a front, left, top perspective view of a fuel transfer pump, showing my new design;

FIG. 2 is a rear, right, bottom perspective view thereof;

FIG. 3 is a front, right, bottom perspective view of the enlarged scale thereof;

FIG. 4 is a front elevational view of the enlarged scale thereof;

FIG. 5 is a rear elevational view of the enlarged scale thereof;

FIG. 6 is a left side view of the enlarged scale thereof;

FIG. 7 is a right side view of the enlarged scale thereof;

FIG. 8 is a top plan view of the enlarged scale thereof;

FIG. 9 is a bottom plan view of the enlarged scale thereof;

FIG. 10 is an enlarged view of detail 10 in FIG. 1;

FIG. 11 is an enlarged view of detail 11 in FIG. 1;

FIG. 12 is an enlarged view of detail 12 in FIG. 1;

FIG. 13 is an enlarged view of detail 13 in FIG. 1;

FIG. 14 is an enlarged view of detail 14 in FIG. 2;

FIG. 15 is an enlarged view of detail 15 in FIG. 2;

FIG. 16 is an enlarged view of detail 16 in FIG. 3;

FIG. 17 is an enlarged view of detail 17 in FIG. 3;

FIG. 18 is an enlarged view of detail 18 in FIG. 6;

FIG. 19 is an enlarged view of detail 19 in FIG. 6;

FIG. 20 is an enlarged view of detail 20 in FIG. 7; and,

FIG. 21 is an enlarged view of detail 21 in FIG. 8.

The dashed broken lines in the figures are for the purposes of illustrating portions of the fuel transfer pump and form no part of the claimed design.

The dash-dot-dash broken lines are for notating enlarged views and form no part of the claimed design.

1 Claim, 21 Drawing Sheets
